UNITED STATES PATENT OFFICE

ARTHUR HERVIEUX, OF BROOKLYN, NEW YORK

SHOE-LAST STAND

Application filed February 10, 1930. Serial No. 427,264.

This invention relates to new and useful improvements in shoe last stands and has for one of its important objects to provide, in a manner as hereinafter set forth, a device of this character which is adapted to be expeditiously swung or adjusted to different positions in a manner to facilitate the various operations in lasting a shoe.

Another important object of the invention is to provide a shoe last stand of the character set forth which embodies means for locking the same in adjusted position.

Another object of the invention is to provide a shoe last stand of the above mentioned character which embodies a swingable last supporting standard which is controlled by a coil spring and which further embodies means for regulating the tension of said coil spring.

Another object of the invention is to provide a shoe last stand which embodies independent adjustable means for supporting the toe portion of the last in a manner to relieve said last of excessive strain or stress when the toe portion of the shoe upper is being nailed.

Other objects of the invention are to provide, in a manner as hereinafter set forth, a shoe last stand which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in side elevation of a shoe last stand constructed in accordance with this invention with a last mounted in position thereon and moved to elevated or adjusted position.

Figure 2 is a view principally in side elevation and partly in section showing the device in lowered position with the toe portion of the last on the supporting head or standard provided therefor.

Figure 3 is a transverse vertical sectional

view taken substantially on the line 3-3 of Figure 2 looking in the direction of the arrows.

Figure 4 is a transverse vertical sectional view taken substantially on the line 4-4 of Figure 2 looking in the direction of the arrows.

Figure 5 is a detail view in top plan illustrating the toe supporting standard.

Referring to the drawings in detail, the reference character 1 designates the outer portion of a work bench or table mounted on the supporting legs 2. A flat metallic bracket 3 extends forwardly from the edge of the work bench 1 and is provided with an integral offset portion 4 abutting the edge of the work bench and terminating in an extension 5 disposed transversely on the upper side of said work bench as clearly seen in Figures 1 and 2, of the drawings. The bracket 3 is secured to the work bench 1 through the medium of the securing elements 6 extending through the offset portion 4 and the extension 5. The outer end portion of the bracket 3 is supported on the upper end of a post 7 and said bracket terminates in a down turned flange 8 secured to the side of said post 7 at its upper end portion through the medium of the securing bolt 9.

The bracket 3 is provided with a longitudinal-slot 10 and mounted on the opposite side of said slot adjacent the outer end of the bracket is a pair of bearing blocks 11 secured in place by the bolts 12. A pin 13 is supported between the bearing blocks 11 for rotation therein and mounted on said pin intermediate the bearing blocks is a last supporting standard 14 having an integral angular extension or arm 15 on its lower end and directly inwardly therefrom.

As illustrated to advantage in Figure 4 of the drawings, the upper end of the standard 14 is socketed to receive the last supporting pin 16 of the last 17, and said standard 14 is further provided with a laterally extending passage 18 for the passage of a suitable tool for facilitating the removal of the pin 16 when it is so desired.

As clearly illustrated in the drawings, the

passage 18 communicates with one side of the standard 14 in spaced relation to the lower end thereof.

Adjacent the inner ends thereof and on opposite sides of the slot 10 the bracket 3 has mounted rigidly thereon and depending therefrom the spaced, parallel co-extensive rods 19 which are connected together at their lower ends by the cross bar 20. An eye bolt 21 extends through an intermediate portion of the connecting bar 20 and is secured thereto by the winged nut 22 and said eye bolt constitutes means for coupling the lower end of a coil spring 23 to said connecting bar. The 15 coil spring 23 extends upwardly between the rods 19 and has its upper end connected to the free end of the arm 15 in a manner to yieldingly pull said arm downwardly and swing the standard 14 in a vertical plane inwardly toward the work bench 1. The arm 15 is adapted for swinging movement through the slot 10 of the bracket 3. The arm 15 is further provided, in its lower edge and adjacent its free end, with a notch or recess 24 20 (see Figure 2) for the reception of a pin 25 adapted to be disposed transversely across the bracket 3 and the slot 10 therein in the manner clearly illustrated in Figure 3 of the drawings. The pin 25 is provided with a 25 knob or handle 26 on one end and adjacent said knob the pin is further provided with an integral angular finger 27 adapted to extend under the adjacent marginal portion of the bracket 3 and adapted to facilitate the proper positioning of the pin on the bracket.

The extension 5 of the bracket 3 constitutes a base for adjustably supporting a post 28 having a concaved upper end for the reception of the toe portion of the last 17 upon which is to be secured the toe portion 29 of the shoe upper. As illustrated to advantage in Figure 3, the upper end of the post conforms substantially to the configuration of the portion of the last which is engaged therein. The extension or base 5 is provided with a centrally disposed longitudinally extending dovetail tongue 30 adapted for disposition in a complementary groove 31 in the lower end of the post 28. The post 28 is further 45 provided with depending flanges 32 formed integrally on the lower end thereof which extends downwardly over the opposite sides of the base 5.

As illustrated to advantage in Figures 1, 2 and 5 of the drawings the dovetail tongue 30 is provided with a series of longitudinally spaced sockets 33 for the reception of a pin 34 which is inserted through an apertured ear 35 formed integrally on the lower end portion of the post 28 on one side thereof. The pin 34 is secured to the post 28 to prevent said pin from becoming lost by a chain 36.

In use, the last may be moved to the position illustrated in Figure 1 for performing certain of the operations and, as will be obvi-

ous, when in this position the last is maintained at a convenient angle to facilitate the work. The device is maintained in this position through the medium of the transversely extending pin 25 which is removably inserted between the arm 15 of the last standard 14 and the bracket 3. When it is desired to secure the toe portion of the shoe upper, the pin 25 is removed and the last is swung to the position indicated in Figure 2 by the coil spring 23. In this position a front support is provided for the forward end of the last and the same is thus relieved of excessive strain. The supporting post 28 may be expeditiously adjusted to accommodate lasts of different length by simply removing the pin 34 and sliding the post 28 longitudinally along the base or extension 5 and then inserting the pin again through the ear 35 and one of the sockets 33.

It is believed that the many advantages of a shoe last stand constructed in accordance with this invention will be readily understood, and although the preferred embodiment of the invention is as illustrated and described, it is to be understood that changes in the details of construction, may be had which will fall within the scope of the invention as claimed.

What is claimed is:—

1. A shoe last stand of the character described comprising a horizontal bracket rigidly mounted on a support in a manner to extend outwardly therefrom, an integral extension formed on one end of the bracket and disposed on the support, said bracket being provided with a longitudinally extending slot, a last supporting standard mounted for swinging movement in a vertical plane on the bracket adjacent the free end thereof, an integral arm formed on the pivoted end portion of the last supporting standard, and adapted for swinging movement through the slot in the bracket, rods depending from the bracket adjacent the inner end thereof, a connecting bar secured between the free ends of the rods, a coil spring connected to the connecting bar, said coil spring also connected to the arm in a manner to yieldingly swing the last supporting standard toward the support, a vertical post mounted for longitudinal adjustment on the extension and engageable with the toe portion of the last in a manner to support the same, and means for securing the vertical post in adjusted position.

2. A shoe last stand of the character described comprising a horizontal bracket rigidly mounted on a support in a manner to extend outwardly therefrom, an integral extension formed on one end of the bracket and disposed on the support, said bracket being provided with a longitudinally extending slot, a last supporting standard mounted for swinging movement in a vertical plane

on the bracket adjacent the free end thereof, an integral arm formed on the pivoted end portion of the last supporting standard and adapted for swinging movement through the 5 slot in the bracket, rods depending from the bracket adjacent the inner end thereof, a connecting bar secured between the free ends of the rods, a coil spring connected to the connecting bar, said coil spring also connected 10 to the arm in a manner to yieldingly swing the last supporting standard toward the support, and a vertical post mounted on the extension and engageable with the toe portion of the last in a manner to support the same.

15 3. A shoe last stand of the character described comprising a horizontal bracket rigidly mounted on a support in a manner to extend outwardly therefrom, an integral extension formed on one end of the bracket and 20 disposed on the support, said bracket being provided with a longitudinally extending slot, a last supporting standard mounted for swinging movement in a vertical plane on the bracket adjacent the free end thereof, an 25 integral arm formed on the pivoted end portion of the last supporting standard and adapted for swinging movement through the slot in the bracket, rods depending from the bracket adjacent the inner end thereof, a 30 connecting bar secured between the free ends of the rods, a coil spring connected to the connecting bar, said coil spring also connected to the arm in a manner to yieldingly swing the last supporting standard toward 35 the support, a vertical post mounted on the extension and engageable with the toe portion of the last in a manner to support the same, and a removable obstructing member engageable with said bracket and bridging 40 the slots therein for engagement by said arm for holding said last supporting standard away from said vertical post against the action of said coil spring.

In testimony whereof I affix my signature.

ARTHUR HERVIEUX.
